JOSEPH M. BROS., OF MINNEAPOLIS, MINNESOTA, ASSIGNOR TO WM. BROS BOILER & MFG. CO., OF MINNEAPOLIS, MINNESOTA, A CORPORATION OF MINNESOTA.

TABLE TOP AND PROCESS OF MAKING THE SAME.

Application filed April 9, 1923. Serial No. 630,957.

To all whom it may concern:

Be it known that I, JOSEPH M. BROS., a citizen of the United States, resident of Minneapolis, county of Hennepin, and 5 State of Minnesota, have invented certain new and useful Improvements in Table Tops and Processes of Making the Same, of which the following is a specification.

In the manufacture of articles such as 10 candy, it is customary to pour the material in a liquid state, from a cooking kettle upon what is known in the art as a cooling table, upon which the candy spreads out by gravity in a thin sheet and is cooled by contact 15 with the surface of the table and by the action of some cooling agent such as water, circulating under or near the bed of the table. The tables used for this purpose are generally about 4 feet wide and from 8 to 10 20 feet long, and to quickly feel the effect of a circulating cooling agent, the table bed is preferably of metal; and to insure uniform thickness of the sheet of candy when cool, it is important that the upper surface of the 25 bed be level and free from waves or ridges. To possess these characteristics, and be of the size required for the table, the bed should be made of a comparatively thick sheet of metal, and to prevent the material 30 in its liquid state from flowing outwardly over the edges of the bed, side and end walls or flanges are provided and these preferably should be made so that there will be no cracks or joints in which the melted material may lodge and detract from the clean 35 sanitary character of the table. Evidently, it would be impracticable to provide removable walls or flanges on the bed, and at the same time avoid the objectionable joints, 40 and the object therefor of my invention is to provide a table bed of the desired thickness having flanged side and end walls from which all objectionable joints and cracks 45 are eliminated and the bed of the table provided with a smooth continuous surface which can easily be kept clean.

A further object is to provide a table bed of inexpensive construction and one which can be made of any desired size. 50 In the accompanying drawings forming part of this specification,

Figure 1 is a sectional view of a blank sheet of boiler plate which I prefer to utilize in the formation of my table bed;

Figure 2 is a perspective view of the under side of the plate after the edges have been planed or milled to form the desired recess or rabbet therein; 55

Figure 3 is a sectional view showing the recess or rabbet in one edge of the plate; 60

Figure 4 is a perspective view showing the completed table top;

Figure 5 is a sectional view showing how the flange at the edge is folded or bent from a horizontal to a substantially upright 65 position;

Figure 6 is a horizontal sectional view on the line 6—6 of Figure 5;

Figure 7 is a detailed sectional view showing the chamber beneath the bed wherein a 70 cooling or heating medium may be circulated.

In the drawing:

I have shown in Figure 1 indicated by numeral 2, a sheet of boiler plate of any 75 suitable thickness. In this particular instance I prefer to use a plate one-half inch in thickness and cut the width and length desired for the dimensions of the table top.

In the longitudinal and transverse edges 80 of this plate, I form a recess or rabbet 3, by planing or milling, in a manner similar to the rabbeting of a wooden plate in the art of wood-working. This recess is of sufficient width and depth to form a flange 4 extending around the edge of the plate on the upper side, the surface of the flange being flush with the top surface of the plate which before the planing or milling operation has been smoothed or planed until it 85 is perfectly flat and free from ridges or indentations. The plate is sufficiently thick so that the top will be firm and rigid and the melted material poured therein will flow outwardly in a thin uniform sheet, spreading 90 over the surface of the plate.

The next step in the formation of the table top consists in bending the flange 4 upwardly in a bending machine or any other suitable apparatus which will turn the flange 100 upwardly, a distance of about 60 degrees from the horizontal, leaving an obtuse angle on the inner side of the flange between it and the top surface of the plate of about 120 degrees; the surface of the flange and the plate merging and forming a gradual unbroken curve as indicated at 5 in Figures 5 and 7, thus eliminating the sharp

105

105

angle or crack that is sometimes formed between the flat surface and an inclined wall encircling the same, and in which material will accumulate and cause unsanitary conditions. The flange is continuous around the plate, and at the corners the side and end walls will be merged forming a rounded surface on the inner side as indicated at 6 in Figure 6; the material at the corners 10 projecting above the side and end walls when the flange is formed being removed by suitable means. Thus when the top is completed, there will be provided a solid substantial bed, rigid under all conditions, 15 having a flat upper surface and upwardly projecting flanges continuous with the bed and forming side and end walls having no sharp angles, joints, or cracks in which the melted material may lodge or which may be 20 difficult to clean and keep in a sanitary condition. The melted material flowing over the smooth metal surface of the bed will cool rapidly and the temperature of the surface of the bed may be kept below normal 25 by mounting the bed over a circulating chamber 7 having suitable connections for maintaining a circulation of cold water continuously in contact with the under surface of the bed.

30 I have shown and described the table top adapted for cooling purposes, but do not wish to confine myself to this use, as a heating means such as steam may be circulated through the chamber 7 in substantially the 35 same manner as the cooling medium for the purpose of heating the bed of the table top. When the flange is bent upwardly around the edge of the plate, the device assumes the form of a shallow pan and may be so used

for various purposes and still be within the 40 scope of my invention.

I claim as my invention:

1. A process of making a table bed which consists in forming a recess in the under side of the peripheral edges of a metal plate 45 leaving a comparatively thin flange projecting horizontally around the upper surface of said plate, then bending said flange upwardly to form integral side and end walls projecting above said bed. 50

2. A process of making a cooling table bed which consists in smoothing one side of a comparatively thick sheet of boiler plate, then milling a rabbet-like recess in the edges of said plate at the sides and ends thereof to form a laterally projecting peripheral flange, and finally bending said flange upwardly to form an integral continuous wall encircling the upper surface 55 of said plate. 60

3. As a new article of manufacture, a table bed comprising a comparatively thick metal sheet having a smooth upper surface and a comparatively thin integral wall flange encircling the upper surface of said sheet, the 65 inner face of said flange and the top of said sheet forming a continuous unbroken surface. 70

4. A table bed comprising a relatively thick metal plate having a relatively thin integral flange encircling its upper surface and projecting upwardly and outwardly therefrom, said flange meeting the surface of said bed and the side flange meeting the end flange in gradual continuous curves 75

In witness whereof, I have hereunto set my hand this 5th day of April, 1923.

JOSEPH M. BROS.
